SEPARATION OF WAX FROM OILS

Chester E. Adams, Hammond, Ind., and Fred W. Scheineman, Chicago, Ill., assignors to Standard Oil Company, Chicago, Ill., a corporation of Indiana

Application March 18, 1932, Serial No. 599,730

19 Claims. (Cl. 196—19)

This invention relates to the separation of wax from oils and it pertains more particularly to an improved system for the use of normally gaseous diluent refrigerants, such as liquid propane.

The object of our invention is to provide a commercial large-scale dewaxing plant for petroleum refineries in which inflammable volatile diluents or refrigerants may be used with safety. In other words, our object is to provide a closed system and means for regulating the pressure in all parts of the system so that leakage of propane will be prevented. We want to avoid the necessity for opening filters and this means, in turn, that we must provide a system whereby the filter leaves will not become clogged with amorphous or finely divided wax. Our object is to provide a special design for filters that will fit into a specially designed filter system to accomplish the continuous dewaxing of oil in a closed system which will not have to be frequently interrupted for repair or cleaning.

A further object of our invention is to provide an improved system and method of chilling diluted oil-wax mixtures so that the optimum wax crystal formation may be obtained. In other words, we want to determine the sequence of steps, the relative volumes of diluent refrigerant and waxy oil in the several steps, the optimum manner and rate of cooling, and the method of handling the crystals which will prevent them from being macerated or deformed prior to filtration. The particular method of crystal formation and the method of handling these crystals is of great importance in a commercial dewaxing system.

A further object of our invention is to provide a system for obtaining maximum mechanical, thermal, and operating efficiency. We want to arrange heat exchangers and chillers so that it will be possible to abstract all of the heat from wax-bearing oil without the use of the conventional wax chillers wherein scrapers are necessary for removing wax from cold walls. We also want to obtain the maximum benefit from the low temperatures of dewaxed oil and diluent so that the expense of refrigeration may be reduced to a minimum.

A further object is to obtain improved lubricating oils having high flash points and low pour points, and to obtain wax which is substantially oil free. Other objects will be apparent as the detailed description of our invention proceeds.

Certain features of our invention may be briefly characterized as follows: In the first place, we employ a dewaxing system which is tied together

by a gas line, all parts of said system being operatively connected with said line. Vaporized propane from all parts of the system are sucked from this line by suitable pumps, compressed, condensed and returned to storage for re-use. 5 This tying together of the whole system by suction gas lines insures safety, and at the same time it enables the temperature of each respective element of the combination to be separately controlled in a very simple and expeditious manner. 10 In other words, the tying together of the whole dewaxing system with a suction gas line makes it possible to employ volatile and expensive refrigerants and diluents which were heretofore too dangerous for commercial use and makes it possible to improve the operation of filters, chillers, etc. so that the operation is uninterrupted over a long period of time.

Another feature of our invention is the combination with our suction gas line of an improved, closed vertical filter in which reverse flow and pressure regulation co-act to remove the filter cake and clean the filter cloth. Another feature of our invention is the combination of "wash propane" and "used wash propane" tanks with the chillers and filters so that practically all of the oil can be removed from the wax without the remelting or redissolving the same in oil or diluent. Another feature is our improved heat exchange 30 system, whereby cold oil-diluent mixtures are used to cool the waxy oil without the formation of wax crystals on the sides of containers so that the use of scrapers is avoided. The invention will be more clearly understood from the following 35 description taken in connection with the accompanying drawings which form a part of the specification and in which similar parts are designated by like reference characters throughout the several views. In these drawings: 40

Figure 1 is a diagrammatic plan of our entire system.

Figure 2 is an elevation of our improved vertical filter, parts thereof being shown in section.

Figure 3 is a horizontal section of said filter taken along the lines 3—3 of Figure 2.

Figure 4 is a vertical section at a filter leaf outlet showing the detail construction of the flexible coupling and showing the insulation at the top joint of the filter.

Figure 5 is an elevational plan of our improved filter element, parts of the same being broken away to illustrate the construction.

Figure 6 is a horizontal section taken along the lines 6—6 of Figure 5.

Figure 7 is a detail section showing the means for holding the filter cloth on the leaf.

Our invention will be described as used for the separation of wax from a treated distillate lubricating oil from Mid-Continent crude petroleum, the particular distillate having a viscosity of about 100 seconds Saybolt at 210° F. and an A. P. I. gravity of 21.3. It should be understood, however, that the invention is equally applicable to any wax-bearing oils.

In the description of our preferred embodiment we will disclose the use of commercial propane as a combined diluent and refrigerant. It should be understood that other normally gaseous hydrocarbons, such as butane, iso-butane, butylene, ethane, ethylene, propane, propylene, etc. may be used either separately or in admixture with each other. By suitably reducing the pressures we may use hydrocarbons in the boiling range of pentane or even hexane. The waxy oil may be diluted all through the system with a small amount of filter naphtha or other light oil which may be useful as a viscosity breaker. Instead of using normally gaseous hydrocarbons we may use normally gaseous ethers such as methyl-ether or we may use chlorinated or fluorinated hydrocarbons such as methyl chloride or dichlor-difluor-methane or oxygenated compounds such as ethylene oxide; the last named substances are useful in the dewaxing process because they have a tendency to throw wax out of solution. We may use normally liquid antisolvents for wax, such as acetone, acid esters, etc. or mixtures of liquid antisolvents with miscibility agents such as benzene or mixtures of benzene with naphtha. If liquids of this type are mixed with the oil they may be considered in the following description as a part of the oil. In our preferred embodiment we effect practically complete dewaxing of the oil by the use of commercial propane.

The propane enters the system through line 10 and is introduced by pipes 11 into storage tanks 12 which are designed to hold the propane at temperatures as high as 95° F. at which temperature the propane may exert a pressure of 165 pounds gauge (above atmospheric). The liquid propane may be selectively removed from one of these storage chambers through line 14, passed through heat exchanger 15, and thence into wash tank 16. The propane is usually at a temperature of 95° F. in line 14 and it is cooled in exchanger 15 to a temperature of about -20° F. The propane in wash tank 16 is cooled to a temperature of -40° F. by the evaporation of a part of the propane, vapors being removed from the tank through conduit 17 and line 18 to compressor 19 which is designed to maintain atmospheric pressure in line 18. The gases may then be passed through pipe 20 to compressor 21 which boosts them to a pressure of about 200 pounds, or compressor 19 may be designed to boost them to this pressure, in which case compressor 21 is cut out by pipe 22. In either case, the highly compressed vapors are passed through line 23 and condensers 24 back to storage tanks 12. The cold propane from wash tank 16 is pumped through pipe 25 by pump 26 to the filter system.

The wax-bearing oil is pumped from storage tank 27 by pump 28 through one branch of pipe 29 into one of the gauging tanks 30, one of these tanks being filled while the other is being emptied. The oil from the gauging tanks is transferred by pump 31 to mixer 32 where it is mixed with propane, forced by pump 33 through pipe 34, and the mixture of waxy oil and propane is cooled in

exchanger 35 to a temperature of about 90° F. to 100° F., this temperature being preferably selected so that the wax will be completely dissolved in the diluted oil. The mixture of wax and diluent is then selectively introduced through one of the pipes 36 into one of the chill chambers A, B, C, or D. When one of these chambers is about one-third full the flow thereto is cut off and the propane-oil mixture is introduced into the following chamber. While this mixture is being charged into the tank the vapor outlets 37 and 38 are preferably closed so that no appreciable cooling by evaporation of diluent takes place.

The cooling of the oil to effect complete precipitation of wax is preferably effected by the introduction of liquefied propane at -40° F. at a rate sufficient to lower the temperature of the oil about 1° per minute. This is accomplished by withdrawing the cooled wash propane from the filter system (which will be hereinafter described) at a temperature of about -40° F. through one of the pipes 39. The physical structure of the crystals has a pronounced effect upon the filter rates attainable and upon the degree of possible wax separation. When the chilled refrigerant is gradually introduced into the diluted oil it appears that the gradual cooling produces large well defined crystals. It may be that the nuclei of these crystals are rather limited in number and that as they move gradually from the point of incoming refrigerant to more removed parts of the chill chamber they gradually increase in size while if the cooling were instantaneous throughout the whole mass of the liquid a much larger number of nuclei would be formed. We do not limit ourselves to any particular explanation of the phenomena, but we have found that this particular method of cooling is remarkably effective in the production of a readily filterable wax slurry.

After a particular chill chamber has been filled two-thirds or three-fourths of its capacity by the addition of cooled propane, the vapor outlet conduit 37 is opened and refrigeration is continued by the direct vaporization of the propane, the vapors being discharged through line 40 into compressor 21 and thence to the condensers 24 and back to the storage containers 12. When the temperature in the chill chamber has been reduced to the desired filtering temperature, the vapor outlet conduit 37 is closed and outlet 38 is opened to vent the chill chamber to the suction gas line which ties together the entire dewaxing system, and which is evacuated by compressor 19.

Thus at about -20° F. to -40° F. the wax slurry is withdrawn through one of the pipes 41, pump 42, line 43, and one of the feed pipes 44 to a vertical filter L, M or N. Pump 42 should be of the rotary, or sliding vane type; if a pulsating pump is used a suitable gas cushioned surge chamber should follow it to obtain uniform, non-pulsating pressure at the filters. These filters will be more particularly described with reference to Figures 2 to 7. Filtrate is withdrawn from the filters by means of one of the pipes 45, each of which is connected with header 46. The original filtrate is then conveyed by gravity through pipes 47 to filtrate receivers 48. When a sufficient cake is deposited on the filter leaves the oil mixture is introduced into the next filter and the cake in the first filter is washed with propane from wash tank 16, line 25, pump 26 and one of the feed pipes 49. When the filters are being washed with propane the so-called "wash propane" filtrate passes by gravity through pipes 50 to "used wash

5 tank" 51 from which it is transferred by pump 52 into pipes 39. The propane in the "used wash tank" 51 is maintained at -40° F. by the vaporization of a part thereof, the vapors being removed 5 through pipe 53 to line 18.

10 We connect the filters to line 18 by valved pipes 54. These valves are closed during actual filter operation, but for purposes of cooling the filter or removing the filter cake, the valves may 10 be opened.

15 Wax is removed from the base of the filter in the manner hereinafter described through one of pipes 55, thence through pipe 56 to wax pumping drum 57. The wax lines are preferably large conduits provided with screw conveyors although 20 in some instances the wax slurry may be pumped by ordinary methods. Wax from drum 57 is forced by pump 58 into high pressure heater 59 which is maintained under a pressure of about 200 25 pounds gauge. Steam coil 60 maintains a temperature in the heater of about 235° F. Liquid wax, together with some propane, is withdrawn from the base of the heater through pipe 61 and passes through regulating valve 62 into atmospheric 30 flash drum 63. Valve 62 is automatically controlled to maintain a constant liquid level in heater 59. The propane vaporized in wax heater 59 is withdrawn through pipe 23 which leads directly to condensers 24. Propane from atmospheric 35 flash drum 63 is withdrawn to line 18.

40 The wax from the base of the flash chamber is withdrawn in amounts controlled by liquid level operated valve 64 and introduced into wax stripper 65 in which steam or other suitable stripping gas may be injected. The steam from the top of the stripper is condensed by the water in jet condenser 66, the liberated propane being vented to propane line 18. Finally the wax which has been freed from oil and propane is forced by pump 67 through cooler 68 into storage tank 69.

45 Returning to the filtrate in tanks 48, this filtrate is withdrawn through one of pipes 70 and pump 70a to heat exchanger 15 wherein it cools the incoming propane which is to be used in washing the filters. The filtrate then passes through heat exchanger 71 and heat exchanger 72 to the top plate of the oil heater 73. Heat may be supplied thereto by steam coil 14 so that a 50 temperature of about 235° F. at a pressure of 200 pounds is maintained in the heater. Oil is withdrawn from the base of the heater by pipe 75 through a regulating valve 76 to low pressure flash drum 77. Regulating valve 76 is automatically controlled to maintain a constant liquid level in heater 73. Propane vapors are removed from the flash drum to line 18. The oil from the base of the flash drum is passed in amounts regulated by liquid level control valve 78 into steam 55 stripping chamber 79 where it is stripped with steam or other suitable gas. The steam is withdrawn through exchanger 71 and thence to jet condenser 80, the liberated propane being returned to line 18.

60 The oil from the base of the stripper 79 is withdrawn through heat exchanger 72 and to oil storage tank 81.

65 It will be observed from the above description that the chill chambers, unused wash propane, used wash propane, filtrate receivers and wax pumping drum are all maintained at temperatures slightly below dewaxing temperatures by the direct vaporization of propane, these vapors being withdrawn by propane line 18 and compressed in compressor 19 to about 200 pounds.

70 It will be understood that suitable valves or pressure regulating means will be installed between the various tanks, filters, chillers, etc. and gas line 18. The chill chambers, filtrate receivers and wax pumping drum will tend to have a temperature, substantially equal to the dewaxing temperature, while the unused wash propane and used wash propane will have a temperature slightly lower than the dewaxing temperature on account of the vapor pressure of pure propane 75 being higher than that of a mixture. Temperatures may be controlled, however, by regulating the valves leading to line 18.

80 If the pressure in the system exceeds about 200 pounds it will be released through vent 82 by 15 the opening of release valve 83. Pressure in the storage tanks 12 is usually about 150 pounds to 165 pounds gauge and use may be made of this pressure to blow the filter cake from the filter leaves (as will be hereinafter described), the propane gas being conducted through line 84 to the respective filtrate discharge pipes 45, suitable by-passes and valves being provided so that propane can be used to discharge the filter cake without interfering with the normal filtrate discharge. 20

85 If desired, propane from line 23 may be bypassed into line 84 by line 85. When gas is used to blow back the filter cake there will be a condensation of propane in the filter cloth due to its 30 cold temperature, and there will be an almost instantaneous boiling or revaporization of this propane due to the low pressure on the other side of the filter cake and, as a result, the filter cake is quickly and thoroughly removed from 35 the filter cloth and the cloth is washed by the reversed flow of propane. The same end may be accomplished by the reverse flow of a slight amount of used wash propane liquid.

90 Before going into detail about filter cake removal we should get a more accurate idea of the structure of this filter by referring to Figures 2 to 7. Each filter is mounted on suitable supports 86 and it consists generally of a vertical, cylindrical wall 87, tapered hopper bottom 88, 45 and concave, tightly fitting removable cover 89. Suspended in the body of the filter or in the cylindrical casing are a plurality of filter leaves 90. Each leaf consists of a reinforcing frame 91, the sides of which are extended and provided with 50 apertured lugs or hooks 92 by means of which the plates may be suspended. The plates or leaves 90 may be spaced by suitable brackets 93, their outer surfaces being about $1\frac{1}{2}$ " to 2" apart. At the bottom of the leaf there is a channel 94 55 to collect filtrate, and this filtrate is removed up through the center of the leaf through flattened conduit 95, flexible conduit 96 and valved outlet 97 to filtrate discharge pipe 45.

60 Each leaf may consist of a coarse screen or perforated plate 98, covered by a finer supporting screen 99 which supports the canvas filter element 100, said element being held in place by suitable buttons 101. These buttons may consist of short bolts 102 extending through the leaf, holding the filter element between washers 103 and 104 (see Figure 7). The filter element is 65 preferably a bag adapted to slide over the frame.

70 The operation of our improved filter is as follows: Propane from tank 51 or tank 16 is first introduced into the filter and evaporated by the removal of vapors through pipe 54 to cool the filter to about -30° or -40° F. It should be noted that the filters and all the conduits handling these cooled liquids are heavily insulated by cork, as 75

bestos or other suitable material 105. When the filter is cooled, the chilled mixture of wax crystals and diluted oil from chillers A, B, etc. is forced by rotary pump 42 into the base of the filter 5 through pipe 44. The rotary pump is designed to move relatively slowly and, in effect, to push the slurry along the pipe without violent agitation and without destroying the structure of the wax crystals. We prefer to maintain a substantially constant flow of filtrate from pipes 45 and we regulate pump 42 accordingly; the pressure on the filter leaves is preferably held below 50 pounds per 10 square inch. Filtrate is forced through the filter medium 100, it collects in channel 94 and is forced 15 up through flattened pipe 95, flexible conduit 96 and outlet pipes 97 to filtrate discharge pipe 45. During the filtering operation it is, of course, necessary to close vapor outlets 54.

Filtration is continued until a cake about 20 $\frac{1}{2}$ " to 1" is built up on the leaf, at which time the flow of the wax slurry is stopped by closing outlet valves in line 45, and the wash propane from tank 16 is introduced at the top of the filter through line 49a. The flow 25 of this liquid propane is continued until all of the unfiltered oil in the filter is forced back (through bypass 42a) to the chillers by displacement. The flow of the wash propane is then changed so as to enter the filter at the bottom 30 and to pass through the wax cake and the filter leaves and out through line 45. The flow of this propane is continued until practically all of the oil is washed out of the wax cake. The first wash propane may contain large amounts of oil and it 35 may therefore be discharged with the filtrate into filtrate receivers 48 through pipes 47. Later amounts of wash propane are removed from the filter leaves through pipe 50 to "used wash propane" tank 51. Propane from the latter tank, as 40 stated above, is used for diluting incoming waxy oil in chillers A, B, C, etc.

Finally the flow of wash propane from tank 16 is stopped and the remaining propane liquid is pumped from the bottom of the filter back to wash 45 tank 16. During this operation a small pressure is maintained inside the filter (outside of the leaves) by means of vapors admitted through lines 84 and 54. To remove the filter cake we may employ a reverse flow of wash propane or we may 50 employ gas from line 84. In either case, liquid propane will be formed in the filter medium and it will be violently expanded by opening the valve in pipe 54, this expansion causing the immediate and thorough removal of the cake from the leaf. 55 The filter cake is directed by the hopper bottom 88 into an enlarged conduit 56 wherein a screw conveys it to wax sump 57. If desired, a spray of liquid propane may be used to assist in washing the outside of the leaves.

60 Precoats or filter aids may be employed to increase filter rates and prevent clogging. Some oils are readily dewaxed with the ordinary filter elements, but other oils show a "cloud" at low temperatures after dewaxing. It is highly desirable that lubricating oil should be "zero-bright". Therefore, in some cases we make a slurry of infusorial earth or other filter-aid in propane or light oil, and apply a precoat to the filter by spraying or by passing some of the liquid through 65 the filter. Other fibrous or crystalline filter aids may be used, either as a precoat or admixed with the wax slurry.

While we prefer to cool the diluted wax-oil mixture as hereinabove described, it should be understood that we may simultaneously remove pro-

pane vapors and add propane liquid to the chillers, we may cool by evaporating propane and subsequently adding more cold propane, or we may add all of the propane before we start to chill by evaporation.

5 While we have described a preferred embodiment of our invention it is to be understood that we do not limit ourselves to any of the details hereinabove set forth except as defined by the following claims, which should be construed as 10 broadly as the prior art will permit.

We claim:

1. In apparatus of the class described, a closed system comprising a propane storage tank, a suction gas line, a compressor and condenser between 15 said gas line and said storage tank, a plurality of chillers, a plurality of filters, a filtrate receiver, a wash propane tank, a used wash propane tank, means for connecting all of said elements to said suction gas line whereby the escape of propane is 20 prevented and whereby the temperature of said elements may be easily controlled by the vaporization of propane.

2. In apparatus of the class described, a closed 25 chill chamber, a closed filter, and a closed filtrate receiver, connections whereby a liquid comprising a liquefied refrigerant may be passed into said chill chamber, thence to said filter, and thence to said filtrate receiver, means for compressing and condensing refrigerant vapors, and a refrigerant 30 vapor line for collecting vapors from said chill chamber, filter and filtrate receiver to said compressing and condensing means whereby the low temperature in various parts of the system may be maintained by vaporization of refrigerant 35 therein.

3. In a dewaxing system for employing a normally gaseous diluent, means for mixing a waxy oil with said diluent, a chill chamber, means for introducing said mixture into the chill chamber, 40 means for withdrawing vapors from said chill chamber whereby the temperature of the oil-wax mixture is reduced at the rate of about 1° to 3° per minute, means for condensing said vapors and returning them for reuse, means including a 45 closed filter for mechanically separating solidified wax from diluted oil, a filtrate receiver, means for removing diluent from said wax and said filtrate, a low pressure gas line, connections from said low pressure gas line to said chill chamber, 50 said filtrate receiver and said diluent removal means, a compressor with its intake side connected to said low pressure gas line, a condenser connected to the discharge side of said compressor, 55 a liquefied diluent storage tank, and means for conducting a condensed diluent from said condenser to said storage tank.

4. In a dewaxing system of the class described wherein a high boiling hydrocarbon is diluted 60 with a diluent having a vapor pressure of about 100 to 200 pounds per square inch at 95° F., the method of separating the diluent from the high boiling hydrocarbon which comprises heating the mixture to a temperature at which the partial pressure of the diluent exceeds its vapor pressure 65 at about 95° F. whereby diluent vapors are drawn from the mixture, cooling said vapors to temperatures of about 95° F. to condense said vapors, flashing the residual oil mixture at about atmospheric pressure to release further amounts of diluent vapors, compressing said released vapors to the pressure of said first named vapors, stripping the flash residue with an inert gas to remove 70 the final diluent vapors and compressing said 75

final diluent vapors with the vapors removed from the flash step.

5. In a dewaxing system of the type described, means for storing a normally gaseous diluent in a liquid state, means for mixing said diluent with wax-bearing oil, means for refrigerating said mixture to dewaxing temperature, a closed pressure filter for separating the wax from the oil-diluent mixture, means for introducing fresh diluent to wash the separated wax in filter, and means for applying said diluent gas from said storage system to remove said separated wax from said filter.

6. In apparatus of the class described, a warm propane storage tank, a cold propane storage tank serving as a reservoir for liquid propane at substantially dewaxing temperature, means for transferring propane from said warm storage tank to said cold storage tank, means for cooling the propane which is so transferred, means for withdrawing propane from the warm storage tank, means for dissolving a waxy oil in said warm propane, means for chilling said solution to form a filterable wax slurry, a closed filter, means for introducing said slurry into said filter, means for introducing cold propane from said cold storage tank into said filter, means for separately removing and storing filter cake and filtrate from said filter, means for removing propane from said filtrate and said filter cake respectively, a low pressure propane gas line connected to said cold propane storage tank, to said cooling means and to said propane recovery means, a condenser connected to said warm propane storage tank, and a compressor with its intake side connected to said gas line and its discharge side connected to said condenser.

7. The apparatus of claim 6 which includes means for effecting heat exchange between said filtrate and the propane which is transferred from the warm storage to the cold storage tank.

8. In apparatus of the class described, a closed system comprising a liquefied propane storage tank, a propane gas line, a compressor and condenser connected between said gas line and said storage tank, means for withdrawing warm propane from the storage tank and for admixing it with waxy oil, a chiller connected with said means, means for transferring vapors from said chiller to said condenser, a closed filter connected to said chiller, means for forcing slurry from said chiller to said filter, a filtrate receiver connected to said filter and to said propane gas line, a wax receiver connected to said filter and to said propane gas line, means connected with said filtrate receiver and said propane gas line for removing propane from the filtrate, and means connected with said wax receiver and said propane gas line for removing propane from wax.

60 9. The apparatus of claim 8 which includes a second propane storage tank, means for introducing propane into said second tank from said first tank, and means for introducing vapors from said second tank into said gas line for cooling the propane in the second tank.

10. The apparatus defined by claim 8 which includes a second propane tank, means for introducing propane from the first storage tank to said second tank, means for transferring heat from said propane to the cold filtrate, and means for removing vapors from the top of said tank and introducing them into said propane gas line.

11. The apparatus of claim 8 which includes an additional propane storage tank, means for introducing propane from said filter to said addi-

tional storage tank, means for introducing propane from said additional storage tank to said chillers, and means for connecting the top of said additional storage tank to said propane gas line.

12. The apparatus of claim 8 which includes means for blowing propane gas from the upper part of said storage tank to said filter.

13. The apparatus of claim 8 which includes a direct connection between said propane recovery means and said condenser whereby said propane is condensed without further compression.

14. In a dewaxing system of the class described wherein a high boiling hydrocarbon is diluted with a diluent having a vapor pressure of about 100 to 200 pounds per square inch at 95° F., the method of separating the diluent from the high boiling hydrocarbon which comprises heating the mixture to a temperature at which the partial pressure of the diluent exceeds its vapor pressure at about 95° F. whereby diluent vapors are drawn from the mixture, cooling said vapors to temperatures of about 95° F. to condense said vapors, flashing the residual oil mixture at about atmospheric pressure to release further amounts of diluent vapors, compressing said released vapors to the pressure of said first named vapors, and stripping the flashed residue to remove the last traces of propane therefrom.

15. In a system for dewaxing a wax-bearing mineral oil by means of a liquefied normally gaseous hydrocarbon diluent such as propane, means for storing liquefied propane at substantially atmospheric temperatures and superatmospheric pressures, means for withdrawing liquefied propane from said storing means and for admixing the withdrawn propane with a wax-bearing oil, a chiller, means for transferring said propane and wax-bearing oil to said chiller, a filter having a wax outlet and a filtrate outlet, means for transferring slurry from said chiller to said filter, a filtrate storage tank connected to said filtrate outlet, a wax storage tank connected to said wax outlet, a high pressure propane recovery still connected to said filtrate tank, a low pressure propane recovery still connected to said high pressure propane recovery still, a similar high pressure propane recovery still connected to said wax tank, a low pressure propane recovery still connected to said high pressure wax-propane still, a propane compressor, a propane condenser connected between the discharge of said compressor and the propane storing means, connections between said high pressure propane recovery stills and said condenser, a low pressure propane gas line, and connections between said low pressure gas line and said chiller, said low pressure filtrate-propane and wax-propane stills respectively.

16. The apparatus of claim 15 which further includes an independent means for passing high pressure propane vapors from said chiller to said condenser.

17. A propane dewaxing system which comprises a tank for storing liquefied propane at ordinary temperatures and superatmospheric pressures, means for mixing about two volumes of propane from said tank with about one volume of wax-bearing oil and for chilling said mixture to effect the solidification of wax in filterable form, a closed pressure filter containing a filter element, means for forcing wax slurry from said chilling means to said filter whereby a wax cake is built up on said filter element and cold filtrate passes through said filter element, a filtrate storage tank connected to said filter, a wax storage tank con-

nected to said filter, a propane recovery system connected to said filtrate storage tank, a separate propane recovery system connected to said wax storage tank, a low pressure propane gas line, a 5 compressor with its suction side connected to said gas line, a condenser connected between said propane storage tank and the discharge side of said compressor, a connection from said low pressure gas line to said chilling means and to each 10 of said propane recovery systems, and means for introducing propane gas into said filter through said filtrate discharge connection whereby wax cake may be dislodged from the filter element by

blowing back with propane without the introduction of non-condensable gases into the system.

18. The system of claim 17 which includes a connection from the upper part of said propane storage tank to said propane blow-back gas 5 means.

19. The apparatus of claim 17 which includes a connection between the propane recovery system and the condenser and a connection from the aforesaid connection to the propane blow-back 10 means for discharging filter cake.

CHESTER E. ADAMS.

FRED W. SCHEINEMAN.
